UNITED STATES PATENT OFFICE

SAMUEL BERNFELD, OF WORCESTER, MASSACHUSETTS, ASSIGNOR TO INTERNATIONAL FOOTWEAR CO. INC., OF WORCESTER, MASSACHUSETTS, A CORPORATION OF NEW YORK

DESIGN FOR A SLIPPER

Application filed November 11, 1929. Serial No. 33,408. Term of patent 3½ years.

To all whom it may concern:

Be it known that I, SAMUEL BERNFELD, a citizen of the United States, residing at Worcester, in the county of Worcester and State of Massachusetts, have invented a new, original, and ornamental Design for Slipper, of which the following is a specification, reference being had to the accompanying drawing, forming part thereof.

The figure is a side view of the slipper, showing my new design.

I claim:

The ornamental design for a slipper as shown.

SAMUEL BERNFELD.
